UNITED STATES PATENT OFFICE.

MELVIN SEARLS, OF STEVENS POINT, WISCONSIN.

DESIGN FOR A STAPLE-EXTRACTOR.

SPECIFICATION forming part of Design No. 32,486, dated April 10, 1900.

Application filed March 12, 1900. Serial No. 8,404. Term of patent 7 years.

To all whom it may concern:

Be it known that I, MELVIN SEARLS, a citizen of the United States, residing at Stevens Point, in the county of Portage and State of Wisconsin, have invented and produced a new and original Design for Staple-Extractors, of which the following is a specification, reference being had to the accompanying drawings, forming part thereof.

10 Figure 1 is a side elevation of a staple-extractor, showing my new design. Fig. 2 is a perspective view, and Fig. 3 is a view looking toward the end of the implement that has the claw formed thereon.

15 The leading or material feature of my design for a staple-extractor consists of a claw formed on one end of a handle, said claw projecting from the under side of the handle at an acute angle therefrom, the outer face being also at an acute angle with the handle, but of a less degree—for instance, a line taken through the center of the handle as a base would be so disposed with relation to the inner side of the claw as to position the 20 angle of said inner side at about seventy degrees, while the outer face a' would be at an angle of fifty degrees with such line, thus providing a wedge-shaped claw A, and the up-

25

per end of the claw a^2 is slightly rounded and at an acute angle with the front edge or line a' . The wedge-shaped claw is provided with an open-ended slot or kerf b, having straight sides, and the ends of the claw are rounded; as shown at c.

A' refers to the handle, which is formed integral with the claw, so that the implement is all in one piece, and this handle adjacent to the claw is rectangular in cross-section; while at a suitable distance from the claw the edges are rounded and the handle tapers slightly.

The staple-extractor is designed for the purpose of drawing staples from fence-posts, said staples being usually employed for holding wire fencing thereto.

I claim—

The design for a staple-extractor, as herein shown and described.

In testimony whereof I have hereunto set my hand in presence of two subscribing witnesses.

MELVIN SEARLS.
